Krikor Atamian,
INVENTOR

BY *Victor J. Evans*

ATTORNEY

WITNESS:

UNITED STATES PATENT OFFICE.

KRIKOR ATAMIAN, OF CORAM, MONTANA.

DUSTING BRUSH.

Application filed May 18, 1927. Serial No. 192,423.

This invention relates to a brush used for dusting powder on certain parts of the body of a person, the general object of the invention being to provide means for holding the brush in upright position through means of a suction cup, with means for fastening the cup to the handle.

This invention also consists in certain other features of construction and in the combination and arrangement of the several parts, to be hereinafter fully described, illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is an elevation of the improved device.

Figure 2 is a section on line 2—2 of Figure 1.

25 Figure 3 is a section on line 3—3 of Figure 1.

In these views, 1 indicates the hollow handle which is provided with an enlarged end 2 having the threads 3 formed thereon for receiving the threaded portion of the 30 cap 4 to which the brush head 5 is fastened by nails or the like. The bristles are shown at 6 and a recess 7 is formed in the inner face of the head, and through the center of the head passes a tapered outlet tube 9, the inner end of which is in communication 35 with the recess. The other end of the handle 1 is closed by means of a weighted plug 10 and the stem 11 of the vacuum cup 12, the stem 11 having a socket therein for receiving a portion of the plug 10 and the stem 11 is held on the plug by means of a split wire 40 ring 13 which is embedded in the stem. The

parts 10 and 11 are held in the handle by means of the annular shoulders 14 engaging the annular grooves 15 formed in the 45 handle.

From the foregoing it will be seen that whenever the bristles of the brush are to have powder placed thereon, it is simply necessary to reverse the brush so that some 50 of the powder in the handle thereof will pass through the discharge tube 9 on to the bristles so that by brushing the parts of the body of a person with these bristles, said parts will be covered with powder. When the handle 55 becomes empty, the cap 4 can be removed and powder placed in the handle through the upper end thereof. The weight 10 and the vacuum cup 12 will act to firmly hold the device in upright position when placed on a 60 flat surface.

It is thought from the foregoing description that the advantages and novel features of my invention will be readily apparent.

I desire it to be understood that I may 65 make changes in the construction and in the combination and arrangement of the several parts, provided that such changes fall within the scope of the appended claim.

What I claim is:—

In combination with a dusting brush having a hollow handle, a plug closing the rear end of the handle and having an outwardly extending reduced portion, a suction cup having a portion fitting in the outer end of the hollow handle, said portion having a socket for receiving the reduced portion of the plug, the handle having annular grooves therein and the plug and suction cup having beads thereon fitting in the grooves for holding the plug and cup in position.

70 In testimony whereof I affix my signature.

KRIKOR ATAMIAN.
